UNITED STATES PATENT OFFICE.

STEPHEN G. WILSON, OF PHILADELPHIA, PENNSYLVANIA.

REMOVABLE HANDLE DEVICE FOR A WHISK BROOM OR BRUSH.

1,192,484.

Specification of Letters Patent. Patented July 25, 1916.

Application filed December 21, 1915. Serial No. 68,027.

To all whom it may concern:

Be it known that I, STEPHEN G. WILSON, a citizen of the United States, residing in the city and county of Philadelphia, State 5 of Pennsylvania, have invented a new and useful Removable Handle Device for a Whisk Broom or Brush, of which the following is a specification.

My invention consists in providing a 10 whisk broom or brush with a removable handle device and appurtenances, adapting the same when said broom or brush is worn-out to be applied to a fresh or new broom or brush, and so render further and con- 15 tinued service.

The invention is satisfactorily illustrated in the accompanying drawing, but the im- 20 portant instrumentalities thereof may be varied, as long as they are included in the scope of the claims.

Figure 1 is a side elevation partly broken away of a handle and appurtenances of a whisk broom or brush embodying my in- 25 vention. Fig. 2 represents a side elevation of a detached sleeve member thereof. Fig. 3 represents a top edge view thereof. Fig. 4 represents the member in Fig. 2, in flat con- 30 dition. Fig. 5 represents a perspective view of a detached hood member thereof. Fig. 6 represents a transverse section on line $\alpha-\alpha$ Fig. 1. Fig. 7 represents a section similar to Fig. 6, showing the key employed in a different position. Fig. 8 represents a plan view of said key. Fig. 9 represents a trans- 35 verse section of the dowel or stub of the broom or brush. Fig. 10 represents an edge view of the bits of said key. Fig. 11 rep- 40 presents a side elevation of the top portion of the broom or brush the handle proper having been removed therefrom.

Similar numerals of reference indicate corresponding parts in the figures.

Referring to the drawings, 1 designates a whisk broom or brush, the same having 45 secured in the head portion 2 thereof the dowel or stub 3, as the primary handle of the broom, see the same projecting in part from said head, as most plainly shown in Fig. 11, whereby it is exposed and made 50 visible in normal condition. Fitted freely on the exposed portion of said dowel is the divided sleeve or ferrule 4, on which are the springs and spurs 5 and 6, the springs

5 projecting inwardly, and the spurs 6 pro- 55 jecting outwardly, it being seen that the springs 5 are adapted to engage with the side of the dowel 3, making a tight fit and causing said sleeve to interlock with the latter, whereby improper disconnection of the sleeve from said dowel is prevented. 60

Fitted on what may be termed the upper portion of the sleeve is the tubular handle 7, whose bore is adapted to be engaged by the spurs 6 of the sleeve 4, whereby said handle is interlocked with said sleeve, so as 65 not to be removable from said sleeve there- after.

In order to further interlock the sleeve 4 with the dowel 3, I form in the walls of the division of the former the recesses 8, said 70 walls forming spring jaws, and in said dowel the opening 9 which is in register with said register and has its walls flaring, as most plainly shown in Figs. 6, 7 and 9. In said opening 9 is inserted the key 10 75 whose bits 11 are flat and spread apart forming springs and adapted to pass through the recesses 8 in the sleeve 4 into said tapering opening 9, said bits being adapted to flare in said opening, and hav- 80 ing on their head end the flat neck 12 which is adapted to engage with the walls or spring jaws of the recesses 8 and have its shoulders freely embrace the walls of the sleeve back of said recesses 8, so as to pre- 85 vent improper withdrawal of the key from the opening in the dowel 3, when hung up, see Fig. 6. The bits are connected with the collar 13 on which is rotatably mounted the ring 14 as the handle or bow of the key, by 90 which the whisk may be hung up. Owing to the division of the sleeve 4, the latter is made expansible and pliable, this being as- 95 sisted by forming in said sleeve the slots 15 which extend inwardly from said division, 95 forming a pair of spring jaws or clamps, so that the said lower portion of the sleeve may be readily separated for a purpose to be hereinafter described.

Fitted on the head of the broom first is 100 the hood 16 which is of the form of a hol- low cap, so as to properly embrace said head, it having in its ends or shoulders the resili- 105 ent tongues 17 which are cut or punched out of the material or metal of said ends or shoulders and remaining at their inner

ends integral with said hood, said tongues being adapted to press inwardly or down against the head or shoulders of the brush, and preventing the straws from pushing up at the shoulders and breaking as is generally the case, thus rendering the same compact, and furthermore, forcing the hood upwardly so that its top is held tightly against the bottom of the sleeve 4, making a tight fit as controlled on the dowel, thus retaining the hood in position, it being noticed that said top has therein the opening 18 to allow the hood to be passed over the dowel in order to be located on the head or shoulder of the broom.

In order to cause the sleeve 4 to retain its shape more true in its expansion and contraction, and prevent torsion thereof, one of the walls of the division thereof is formed 20 with the laterally projecting tongue 19, which is adapted to enter the recess 20, in the other wall of said division and play freely therein, the effect of which is evident.

It will be seen that when the hood is positioned, the spreading bits of the key forming springs are inserted into the tapering opening of the dowel, as shown in Fig. 7, the spreading of the key holding it in position. Then the sleeve with the handle is 25 slipped over the dowel to full extent, its division or clamping parts passing freely over the flat sides or edge portion of the neck 12 of said bits or key, as in said Fig. 7, the springs 5 of the sleeve now taking hold 30 of the dowel. The handle 7 is first fitted on the sleeve in the manufacture and is never removed or separated therefrom thereafter, it remaining connected therewith owing to the spurs 6 on the latter. The key is then 35 turned whereby the neck 12 thereof is at a right angle to the position shown in Fig. 7, so that the shoulders of said neck take hold of the inner walls of the recesses 8, thus tightly locking the sleeve with the handle to 40 the dowel through the medium of the key, it being evident that the broom may be used and manipulated by the handle 7, as usual.

When the broom wears out the key is turned to the position shown in Fig. 7, thus 45 releasing the sleeve of the holding action of the neck of the bits when the sleeve and handle may be removed from the dowel, sufficient force being employed to overcome the springs 5, the handle remaining on the sleeve. The hood is also removed and the several members may be applied to a new broom in the manner hereinbefore stated, making the 50 whisk renewable, and so render further service.

Having thus described my invention what I claim as new and desire to secure by Letters Patent, is:

1. In a removable handle and sleeve device for a whisk broom, the latter being provided with a dowel in the head portion

thereof, a handle and divided sleeve adapted to be fitted on said dowel, the walls of the division of said sleeve forming spring jaws and a divided key member having its bit adapted to be passed through said sleeve 70 into said dowel, and to interlock with the walls of the division or spring jaws of the sleeve.

2. In a removable handle and sleeve device for a whisk broom, the latter being provided with a dowel in the head portion thereof, an expansible divided sleeve adapted to be fitted on said dowel and having therein a slot extending laterally from the 75 division of the sleeve.

3. In a removable handle device for a whisk broom, the latter being provided with a dowel in the head portion thereof, an expansible sleeve adapted to be fitted on said dowel, and means for interlocking said sleeve with said dowel, said sleeve being divided in the direction of its length and having on the walls of the division, a tongue and recess respectively, said tongue being adapted to be guided in said recess and 80 freely retained therein in the expansion and contraction of the sleeve.

4. A removable handle device applicable to the dowel of the head portion of a whisk broom comprising a handle proper, a sleeve 95 adapted to be fitted on said dowel and carry said handle proper, and a key member adapted to be passed through said sleeve into said dowel and secure said sleeve to said dowel.

5. In a removable handle device applicable to the dowel of the head portion of a whisk broom, a sleeve adapted to be fitted on said dowel, and a handle proper adapted to be carried by said sleeve, the latter being provided with an inturned spring member, and an outturned stud member, said stud member being adapted to engage the inner wall of said handle proper, and said spring member being adapted to engage the side of 100 said dowel.

6. In a removable handle device for a whisk broom, the latter being provided with a dowel in the head portion thereof, a divided sleeve adapted to be fitted on said dowel, the walls of the division of said sleeve forming spring jaws, a handle proper on said sleeve, said dowel having a tapering opening therein, and a key having spreading bits adapted to pass through said sleeve into 115 said opening, the neck of said bits being adapted to engage with said walls or spring jaws of the division of said sleeve.

7. In a removable handle device for a whisk broom, the latter being provided with a dowel on the head portion thereof, a sleeve on said dowel, means for locking said sleeve in position, a hood adapted to be fitted on said head portion and having thereon resilient tongues adapted to press down or in- 120

wardly on said head portion and said hood upwardly engaging said sleeve.

8. In a whisk broom having a dowel in the head portion thereof, a sleeve on said dowel, 5 a hood adapted to be fitted on said portion, and having the top thereof adapted to be fitted over said dowel, and its ends or shoulders provided with resilient tongues adapted

to press inwardly and down against said head portion, and said hood upwardly 10 against said sleeve.
